ADJUSTABLE OARLOCK

Marshall T. Michael, Perry, Kans.

Application November 10, 1948, Serial No. 59,239

1 Claim. (Cl. 9—26)

1

This invention relates to a novel adjustable oarlock or rowlock of the type which is adapted to be secured detachably and adjustably to the loom of an oar by an adjustable clamping engagement therewith so that the oarlock is detachably but securely fixed to the oar.

Another object of the invention is to provide an oarlock in which the oar can readily pivot in a vertical plane without subjecting the loom of the oar to wear.

A further and primary object of the present invention is to provide an oarlock for accomplishing the aforescribed results of extremely simple construction which is capable of being economically manufactured and sold and which will be very durable and efficient for its intended purpose.

Various other objects and advantages of the invention will hereinafter become more fully apparent from the following description of the drawing, illustrating a preferred embodiment thereof, and wherein:

Figure 1 is an elevational view of the oarlock shown in an applied position and looking at the oarlock as it would appear looking from either end of an oar engaged thereby;

Figure 2 is a sectional view thereof, partly in side elevation, taken substantially along a plane as indicated by the line 2—2 of Figure 1, and

Figure 3 is a sectional view of the oarlock taken substantially along a plane as indicated by the line 3—3 of Figure 2.

Referring more specifically to the drawing, the novel oarlock in its entirety is designated generally 5 and includes a support, designated generally 6, a clamp, designated generally 7 and a combination fastening and pivot 8.

The oarlock support 6 includes a stem or shank 9 which depends from its integral disk-like head 10 and which is disposed substantially perpendicular to said head. The oarlock support 6 also includes an ear 11 which is formed integral with and rises from the opposite, upper side of the head 10 and which is provided with an opening 12.

The clamp 7 comprises a relatively wide substantially ring-shaped band which may be formed of any suitable relatively resilient metal having corresponding outturned terminals 13 which are provided with correspondingly disposed openings 14. The outturned terminals 13

form a gap in the substantially ring-shaped portion 15 of the clamp 7. Said portion 15 is adapted to be positioned around a portion of the loom 18 of a conventional oar after which the ear 11 is inserted between the terminal portions 13. The fastening 8 which includes a bolt 16 and nut 17 is then applied by inserting the threaded shank end of the bolt 16 through the aligned openings 14 and 12 of the terminals 13 and ear 11. The nut 17 is then applied to the threaded shank end of the bolt and tightened against the outer side of one of the terminals 13 and so that the head of the bolt 16 will engage against the outer side of the other terminal 13. By tightening the nut 17, the ring portion 15 of the clamp 7 will be drawn into clamping engagement with the oar loom 18. With the clamp 7 of a proper size for a particular oar loom, when the loom is securely clamped in the ring portion 15, the terminals 13 will be disposed substantially parallel to one another and with the ear 11 loosely disposed therebetween. Said ear 11 has its opening 12 engaging an unthreaded portion of the shank of the bolt 16, as seen in Figure 3, which portion 25 is free to rotate in the opening 12 to permit the clamp 7 to rock on the support 6 so that the oar loom 18 can swing in substantially a vertical plane. It will be readily apparent that the position of the oarlock 5 on the oar loom 18 can be varied as desired by merely loosening the fastening 8 and slidably adjusting the clamp 7 on the oar loom after which the fastening 8 can again be tightened as previously described.

From the foregoing it will be readily apparent that an oarlock of extremely simple construction has been provided including a minimum of parts and wherein the fastening 8 functions not only as a pivot between the support and clamp but also as an actuator for moving the clamp into an operative position.

Various modifications and changes are contemplated and may obviously be resorted to, without departing from the spirit or scope of the invention as hereinafter defined by the appended claim.

I claim as my invention:

An adjustable oarlock comprising a support having an upstanding ear, a clamp adapted to detachably and adjustably engage an oar loom, and means rotatably engaging said ear and pivot-

ally connecting the clamp and support and providing an adjustable clamp actuator, said clamp comprising an uninterrupted relatively wide split band of relatively resilient material having a substantially ring-shaped intermediate portion 5 adapted to engage around the oar loom and out-turned apertured terminal portions loosely straddling said ear and receiving said pivotal means, said pivotal means comprising a nut and bolt, and said ear having an aperture registering with 10 the apertures of said outturned terminal and receiving the bolt shank, said bolt shank having an unthreaded portion journaled in the aperture of the ear.
